US0D1102421S

(12) **United States Design Patent** (10) **Patent No.:** **US D1,102,421 S**
(45) **Date of Patent:** ** *Nov. 18, 2025

(54) **SMART GATEWAY**

(71) Applicant: **Siemens Industry, Inc.**, Alpharetta, GA (US)

(72) Inventor: **Rong Cao**, Shanghai (CN)

(73) Assignee: **Siemens Industry, Inc.**, Alpharetta, GA (US)

(*) Notice: This patent is subject to a terminal disclaimer.

(**) Term: **15 Years**

(21) Appl. No.: **29/868,347**

(22) Filed: **Nov. 30, 2022**

(57) **CLAIM**

The ornamental design for a smart gateway as shown and described.

DESCRIPTION

FIG. 1 is a right side view of a smart gateway embodying the invention;

FIG. 2 is a left side view thereof;

FIG. 3 is a top view thereof;

FIG. 4 is a bottom view thereof;

FIG. 5 is a back view thereof;

FIG. 6 is a front view thereof;

FIG. 7 is a perspective view thereof;

FIG. 8 is a right side view of another smart gateway embodying the invention;

FIG. 9 is a left side view thereof;

FIG. 10 is a top view thereof;

FIG. 11 is a bottom view thereof;

FIG. 12 is a back view thereof;

FIG. 13 is a front view thereof;

FIG. 14 is a perspective view thereof;

FIG. 15 is a right side view of another smart gateway embodying the invention;

FIG. 16 is a left side view thereof;

FIG. 17 is a top view thereof;

FIG. 18 is a bottom view thereof;

FIG. 19 is a back view thereof;

FIG. 20 is a front view thereof; and,

FIG. 21 is a perspective view thereof.
